Primary Examiner — Dana K Weiland*Assistant Examiner* — Elizabeth Anne Glassberg(74) *Attorney, Agent, or Firm* — Nitin Kaushik(57) **CLAIM**

The ornamental design for a dog raincoat, as shown and described.

DESCRIPTION

FIG. 1 is a front perspective view of a dog raincoat, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a top perspective view thereof, shown in an alternate configuration with the body flattened.

The thin broken lines in the drawings illustrate the portions of the dog raincoat, which form no part of the claimed design.

The thick broken lines representing stitching are part of the claimed design.

1 Claim, 8 Drawing Sheets(56)
